DESIGN FOR A TOOTHBRUSH

Meyer E. Dolnick, Chicago, Ill.

Application September 10, 1945, Serial No. 121,975

Term of patent 7 years

(Cl. D9—2)

To all whom it may concern:

Be it known that I, Meyer E. Dolnick, a citizen of the United States and resident of Chicago, in the county of Cook and State of Illinois, have invented a new, original, and ornamental Design for a Toothbrush, of which the following is a specification, reference being had to the accompanying drawing, forming a part thereof.

Fig. 1 is a top plan view of the toothbrush embodying my new design.

Fig. 2 is a side elevational view thereof.

I claim:

The ornamental design for a toothbrush, substantially as shown.

MEYER E. DOLNICK.
